TEXTILE PRINTING MACHINE

Louis Galan, Pittsburgh, Pa.

Application December 2, 1949, Serial No. 130,683

6 Claims. (Cl. 101—122)

1

This invention relates generally to a textile printing machine and more particularly to a machine employing an air jet to force liquid dye through the fabric.

A primary object of this invention is to provide a textile printing machine of simple character which will assure the localized dyeing of portions of the cloth to give the effect of printing on each side of the cloth, that is, the same pattern is applied to both sides and every fiber is colored thoroughly.

Another object of this invention is to provide a machine which will color print fabrics with very little waste of dye in the process, since means is provided for retaining the excess dye for reuse.

Another object of this invention is to provide a comparatively simple machine which can effectively use liquid dye with consequent saving in operational costs.

Still another object of this invention is to provide a machine of this character which can be used as part of equipment for a continuous processing of long lengths of cloth.

Still another object of this invention is to provide a machine of this general character, wherein the pattern is inexpensively produced and easily installed in the machine.

Another object of this invention is to provide a machine of this general character in which the cloth being printed is made to progress through the machine without danger of misplacement and faulty or double printing is positively prevented.

And a last object to be mentioned specifically is to provide a machine of this general character which is relatively inexpensive and practical to manufacture, which is simple, safe and convenient to operate, and which will give generally efficient and durable service.

With these objects definitely in view, this invention resides in certain novel features of construction, combination and arrangement of elements and portions as will be hereinafter described in detail in the specification, particularly pointed out in the appended claims, and illustrated in the accompanying drawings, which form a material part of this application, and in which:

Figure 1 is a side elevational view of the assembled machine;

Figure 2 is a top plan view of the machine;

Figure 3 is a vertical longitudinal sectional view; fragmentary in character, taken substantially upon the line 3—3 in Figure 2;

2

Figures 4 and 5 are vertical transverse sectional views taken on the irregular section line in Figure 1 and looking in the direction of the respective arrows;

Figure 6 is a fragmentary view of a portion of the machine, in perspective, designed to show more particularly the positional relationship of the table, soaking cloth, pattern, and the cloth being printed;

Figure 7 is a view of the main portion of the dye supply means and a section of the soaking cloth; and

Figure 8 is a vertical sectional view, considerably enlarged, of the main portion of the air jet or fluid pressure means, used to drive the fluid dye through the fabric, the figure being particularly designed to illustrate how the jet opening is made adjustable.

Similar characters of reference designate similar or identical elements and portions throughout the specification and throughout the different views in the drawings.

Referring now to the drawings in detail, this invention relates to that portion of a printing establishment used for actually applying liquid dye to lengths of cloth. The machine includes a flat topped table 10 having parallel rollers 12 rotatably mounted on each end of the machine, with the upper edges of the rollers substantially coplanar with the top of the table. A motor 14 is used to drive one of these rollers 12 by means of a belt 16, this last mentioned roller having a pulley 18. An endless conveyor 20 is operatively mounted on and between the rollers 12, the upper flight of the conveyor 20 sliding longitudinally along the top of the table 10.

An aperture 22 is provided in the table 10 and a pair of parallel rollers 24 are mounted on arms 26 pivoted on brackets 28 on the underside of the table 10 at each side of the aperture 22, and springs 30 are secured between outer ends of the arms 26 and a cross brace 32 of the table to bias the rollers 24 upwardly against that portion of the conveyor 20 which is above the aperture 22.

A frame 34 is of open character and straddles the table 10 so that support is provided for rollers 36 and 38 which are arranged parallel to each other, transversely of the conveyor 20 and spaced thereabove a small distance. One of these rollers, represented at 36, is provided with a pulley 40 and a belt 42 connects this roller with the pulley 18 which is of double character. The other roller 38 is adjustable, as indicated at 44, and a soaking cloth 46 of endless belt char-

acter is entrained over these rollers 36 and 38. The soaking cloth 46 is porous but is not of soft material. A porous and reasonably thick canvas may be used. In this regard, it should be carefully noted that the thickness of the soaking cloth will vary according to the thickness and character of the cloth to be printed, thicker soaking cloths being ordinarily required for processing thicker fabrics. The lateral edges of the soaking cloth 46 are rendered non-porous, ordinarily by the addition of adhesive substances, and these impervious edges prevent liquid dye from passing through the soaking cloth, excess at the central portions thereof.

An endless pattern 50 having apertures 52 therein is operatively mounted superficially of the soaking cloth 46 to revolve therewith around the rollers 36 and 38. The pattern and soaking cloth will be substantially coextensive in length with the rollers 36 and 38. The cloth to be printed, indicated at 54, will be placed between the pattern and the conveyor 20 and will be fed along with the conveyor and the pattern and soaking cloth, the adjacent portions of which will, of course, move at an equal rate along the top of the table 10.

It may be here noted that the conveyor 20 is also porous and will ordinarily be fine meshed cloth of rust-proof steel, bronze, nylon or other suitable material. The soaking cloth and pattern, as well as the conveyor 20 are each easily replaceable.

A liquid dye tank 56 is supported by bracket 58 upon the top of the frame 34 and a valved pipe 60 leads from the tank 56 to a distributor head 62, which distributor head is bounded by means of other brackets 64, upon the frame 34. The distributor head 62 has a depending neck 66 extending longitudinally of the distributor head and transversely of the soaking cloth 46 and the lower end of the distributor head contacts this soaking cloth on the inner surface of the lower flight thereof. The neck 66 is provided with a slot 69 and flanges 68 curve upwardly from each side of the lower end of the neck 66, in order that the fraying of the soaking cloth be reduced to a minimum.

Fluid pressure means to drive the liquid dye from the soaking cloth through the pattern and into the fabric 54 includes a pipe 70 disposed transversely of the machine and slightly above the lower flight of the soaking cloth 46, and on the side of the distributor head 62 toward which the soaking cloth 46 moves after contact with the distributor head. This pipe 70 may be substantially coextensive in length with the distributor head 62 and with the soaking cloth 46, and the pipe is rigidly secured on the frame 34 by suitable brackets 72. A source of pressurized air 74, diagrammatically illustrated, will be provided and operatively connected with the pipe 70. The pipe 70 is provided with end plates 76, closing the end of the pipe and supporting pairs of rollers 78, one at each side of the pipe 70 and in contact with the inner surface of the lower flight of the soaking cloth 46. A depending neck 82 extends along the lower side of the pipe 70 and this neck terminates in flanges 84, one of which is upturned to lessen the fraying of the soaking cloth 46, while the other is provided with a slot 85 to receive a bolt 86 which adjustably secures a plate 88 in coplanar relationship with the other flange 84, so that the jet opening 87 is made adjustable, all as will be clearly understood from a consideration of Figure 8.

A collector for excess fluid dye is provided, this collector including an elongated funnel 90 extending transversely of the aperture 22 in the table, a tank 92, ordinarily supported on the cross brace 32 of the table and a drain pipe 94 which may be valved if desired. The neck 82 of the fluid pressure means has a vertical slot 96 with the jet opening 87, already mentioned, aligned with the funnel 90, and it will be readily understood that excess fluid dye will be collected in the tank 92, the preferred positioning of the funnel 90 being as illustrated in the drawings between the rollers 24.

The operation of this invention will be clearly understood from a consideration of the drawings and the above description of the mechanical details thereof, taken in connection with the specifically recited objects in the preamble of the specification. Further description would appear unnecessary.

Having described the invention, what is claimed as new is:

1. A textile printing machine comprising a flat topped table having an opening therein, an endless reticulated cloth-carrying conveyor traveling horizontally over said table and opening, a pair of parallel rollers one on each side of said opening and spaced slightly above the conveyor, an endless soaking cloth operatively mounted on the rollers with a straight lower run parallel with said conveyor, an endless apertured pattern disposed exteriorly on said soaking cloth and carried thereby so that the pattern is between said soaking cloth and conveyor during a portion of each revolution of the pattern, dye supply means applying dye to said lower run to impregnate the soaking cloth with dye, fluid pressure means to drive the dye from the soaking cloth through the apertures in said pattern, and power means to operate said rollers and conveyor, said pattern being endless and superimposed on said endless soaking cloth.

2. A textile printing machine comprising a flat topped table having an opening therein, an endless reticulated cloth-carrying conveyor traveling horizontally over said table and opening, a pair of parallel rollers one on each side of said opening and spaced slightly above the conveyor, an endless soaking cloth operatively mounted on the rollers with a straight lower run parallel with said conveyor, an endless apertured pattern disposed exteriorly on said soaking cloth and carried thereby so that the pattern is between said soaking cloth and conveyor during a portion of each revolution of the pattern, dye supply means applying dye to said lower run to impregnate the soaking cloth with dye, fluid pressure means acting against said lower run to drive the dye from the soaking cloth through the apertures in said pattern, and power means to operate said rollers and conveyor, said pattern being endless and superimposed on said endless soaking cloth, said table having spring biased rollers within said opening to support the conveyor.

3. A textile printing machine comprising a flat topped table having an opening therein, an endless reticulated cloth-carrying conveyor traveling over said table and opening, a pair of parallel rollers one on each side of said opening and spaced slightly above the conveyor, an endless soaking cloth operatively mounted on the rollers, an endless apertured pattern disposed exteriorly on said soaking cloth and carried thereby so that the pattern is between said soaking cloth and conveyor during a portion of each revolution of

the pattern, dye supply means to impregnate the soaking cloth with dye, fluid pressure means to drive the dye from the soaking cloth through the apertures in said pattern, power means to operate said rollers and conveyor, said pattern being endless and superimposed on said endless soaking cloth, said table having spring biased rollers within said opening to support the conveyor, a collector for excess dye beneath the conveyor, said dye supply including a distributor head having a slot extending transversely of the soaking cloth and in contact therewith, and an upwardly curved flange on one side of said slot, said fluid pressure means including a pipe extending transversely of an above a portion of the soaking cloth adjacent the aperture in the table, a neck depending from the pipe and extending longitudinally of the pipe and having a vertical slot therein, flanges on both sides of the lower end of said pipe extending outwardly from said slot in the pipe, a plate adjustably mounted on one of said flanges for controlling the effective opening of said slot, and a source of pressurized air connected with said pipe.

4. A textile printing machine comprising a flat topped table having an opening therein, an endless reticulated cloth-carrying conveyor traveling over said table and opening, a pair of parallel rollers on each side of said opening and spaced slightly above the conveyor, an endless soaking cloth operatively mounted on the rollers, an endless apertured pattern disposed exteriorly on said soaking cloth and carried thereby so that the pattern is between said soaking cloth and conveyor during a portion of each revolution of the pattern, dye supplying means to impregnate the soaking cloth with dye, fluid pressure means to drive the dye from the soaking cloth through the apertures in said pattern, and power means to operate said rollers and conveyor, said dye supply means including a distributor head having a slot extending transversely of the soaking cloth and in contact therewith, and an upwardly curved flange on one side of the slot.

5. A textile printing machine comprising a flat topped table having an opening therein, an endless reticulated cloth-carrying conveyor traveling over said table and opening, a pair of parallel rollers one on each side of said opening and spaced slightly above the conveyor, an endless soaking cloth operatively mounted on the rollers,

an endless apertured pattern disposed exteriorly on said soaking cloth and carried thereby so that the pattern is between said soaking cloth and conveyor during a portion of each revolution of the pattern, dye supply means to impregnate the soaking cloth with dye, fluid pressure means to drive the dye from the soaking cloth through the apertures in said pattern, and power means to operate said rollers and said conveyor, said fluid pressure means including a pipe extending transversely of an above a portion of the soaking cloth adjacent the aperture in the table, a neck depending from the pipe and extending longitudinally of the pipe and having a vertical slot therein, flanges on both sides of the lower end of said pipe extending outwardly from said slot in the pipe, a plate adjustably mounted on one of said flanges for controlling the effective opening of said slot, and a source of pressurized air connected with said pipe.

6. A textile printing machine comprising a flat topped table having an opening therein, an endless reticulated cloth-carrying conveyor traveling horizontally over said table and opening, a pair of parallel rollers one on each side of said opening and spaced slightly above the conveyor, an endless soaking cloth operatively mounted on the rollers with a straight lower run parallel with said conveyor, an endless apertured pattern disposed exteriorly on said soaking cloth and carried thereby so that the pattern is between said soaking cloth and conveyor during a portion of each revolution of the pattern, dye supply means to impregnate the soaking cloth with dye, fluid pressure means to drive the dye from the soaking cloth through the apertures in said pattern, and power means to operate said rollers and conveyor.
